V. Brown.

Canal Gate Signal.

9647X

Patented May 14, 1836.

Valentine Brown.

Letters Patent.

The schedule referred to in these Letters Patent and making part of the same, containing a description in the words of the said Valentine Brown, himself of his improvement in the light and other apparatus for indicating to canal boats when the gates are open or closed.

To all to whom these presents shall come,

Be it Known that Valentine Brown, of the Town of Briston Park in the County of Oneida and State of New York have invented a new and useful improvement in the light and other apparatus, for indicating to travellers, or boats, where the gates are open or closed on canals; and that the following is a full and exact description of the same.

My improvement consists in the use of lights or other suitable devices to show travellers on board of canal boats whether the gates are open or closed. The apparatus may consist of a lamp fixed on the top of an upright rod. This rod is allowed to turn horizontally 90 degrees or $\frac{1}{4}$ of the way round, being supported by means of eyebolts or other suitable fixtures in a lamp post. From the bottom of the upright on which the lamp is placed a projects an arm to which is attached a hinge rod; this rod passes horizontally to the full run upright of the gate, having a working connection with it. By means of this hinge rod it is planned to be perceived that, when the gate is opened or closed a different side of the lamp, frame or apparatus is presented to the line of the canal. Two lamps and apparatus may be used at each lock, one to give a red light to represent the lock open, the natural light when the lock is closed.

I claim the principle by which I indicate that
